UNITED STATES PATENT OFFICE.

LANDRETH W. EVANS, OF RITZVILLE, WASHINGTON.

SANITARY ICE-CREAM-CONE CARRIER.

1,260,528.

Specification of Letters Patent. Patented Mar. 26, 1918.

Application filed September 13, 1917. Serial No. 191,237.

To all whom it may concern:

Be it known that I, LANDRETH W. EVANS, a citizen of United States, residing at Ritzville, in the county of Adams and State 5 of Washington, have invented certain new and useful Improvements in Sanitary Ice-Cream-Cone Carriers; and I do declare the following to be a full, clear, and exact description of the invention, such as will enable others skilled in the art to which it 10 appertains to make and use the same.

This invention relates to improvements in cone-carriers and has for its primary object the provision of an article of this character 15 in which ice cream cones may be carried without permitting dirt or dust coming in contact with the cream.

Another object is to provide a device of this character which is simple and inexpensive in construction, and highly efficient 20 in its purpose.

With these and numerous other objects in view my invention resides in the novel features of construction, and in the combination 25 and arrangement of parts as set forth in the specification and claim and clearly illustrated in the accompanying drawings in which:

Figure 1 is a plan view of the box blank. 30 Fig. 2 is a perspective view of the box with one side open and showing the cone-carrier in use.

Fig. 3 is a perspective view of the box in closed position.

Fig. 4 is a vertical longitudinal section of the box in closed position.

Fig. 5 is a horizontal section on the plane of line 5—5 of Fig. 4, and

Fig. 6 is a detail section on the plane of line 6—6 of Fig. 4 showing the means of attaching the cone support.

Similar numerals of reference are employed to indicate corresponding parts throughout the several views.

In the embodiment of my invention as set forth in the accompanying drawings, the box is substantially rectangular and includes a pair of oppositely disposed side walls (1), one wall having at each end a vertically 45 extending box end section 2 of a width substantially one-half that of the box, each section being folded inwardly on the line 3 indicated in the drawings. Each of the sections 2 is provided with a pair of vertically 50 spaced tongues 4 on its free edge, whose function will be hereinafter set forth.

The other side wall is provided at each end with a box end section 5 of substantially the same width as that of the box and having a pair of vertically alined and disposed slits 6 in which are received the tongues 4 on the adjacent end section 2 when the box is being assembled, the slotted sections folding on the lines 7 as indicated in the drawings. The side walls are connected 60 at their lower ends by the bottom section 8 which extends the length of the box and is provided at each end with a tongue 9 adapted to be folded inwardly to close the space 65 between the end section and bottom of the 70 box.

One of the side-walls 1 is provided at its upper longitudinal edge with a rectangular cover 10 which has on its free longitudinal edge a flap 11 adapted to be folded inwardly 75 and contact with the inner face of the opposite wall. For the purpose of closing the box against the entrance of dirt or the like the box end sections 5 are each provided at their upper ends with flaps 12 which fold 80 inwardly longitudinally beneath the cover 10. In order that the box may be easily carried around a handle 13 of any suitable material and construction is provided.

For the purpose of carrying ice cream 85 cones or the like, in the box in an upright position the box is provided with a rectangular strip of material 14 of substantially the same length as the interior length of the box and substantially the same width. 90 The strip is provided with a longitudinal attaching portion 15 which is connected to one of the side walls 1 at a point substantially midway its height. The main body of the strip 14 has a plurality of horizontally spaced openings 16 through which the lower ends of the cones are projected into contact with the bottom 8 of the box so as to form a firm support.

It is to be observed (see Figs. 4 and 5) 100 that the area of the shelf 14 is slightly less than the horizontal cross sectional area of the complete box or carton. By this arrangement, the shelf in question may yield downwardly to a slight extent when the 105 cones are dropped into the openings 16 and thus there will be no danger of breaking said cones as would undoubtedly occur if the shelf were rigidly supported.

From the foregoing description of the 110 construction and operation of my improved ice cream cone holder, the operation will be

clearly understood and it is also to be understood that numerous changes in the details of construction may be made without sacrificing the principal advantage.

5 I claim:

An article of manufacture comprising a flat blank of card board cut to form the sides, ends, top and bottom of a carton to contain an ice cream cone, and a rectangular 10 card board shelf lying flat upon the upper half of one of said sides and secured along its lower edge thereto, said shelf being adapted to be folded downwardly to a horizontal position when the blank is folded to 15 form the carton and having an opening to

receive the cone, said shelf being of less area than the horizontal cross sectional area of the carton and having no supporting means other than its secured edge, whereby said shelf may yield downwardly when the cone 20 is inserted and will thus have no tendency to crack the latter.

In testimony whereof I have hereunto set my hand in the presence of two subscribing witnesses.

LANDRETH W. EVANS.
